[57] CLAIM

The ornamental design for an electrical connector application tool, as shown and described.

DESCRIPTION

FIG. 1 is a perspective view of an electrical connector application tool showing my new design;

FIG. 2 is a top view thereof;

FIG. 3 is a bottom view thereof;

FIG. 4 is a side elevational view of the tool of FIG. 2, the opposite side being a mirror image thereof;

FIG. 5 is an end view thereof showing the left-hand end of the tool of FIG. 2; and

FIG. 6 is an end view thereof showing the right-hand end of the tool of FIG. 2.

FIG. 1

FIG. 2

FIG. 5
